[57] CLAIM

The ornamental design for an orthopedic surgical table,
substantially as shown.

DESCRIPTION

FIG. 1 is a front perspective view of an orthopedic
surgical table showing my new design;

FIG. 2 is a side elevation thereof;

FIG. 3 is a top plan view thereof;

FIG. 4 is one end elevational view thereof;

FIG. 5 is another end elevational view thereof; and

FIG. 6 is a bottom plan view thereof.
